UNITED STATES PATENT OFFICE.

SAMUEL M. VAUCLAIN, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

LOCOMOTIVE-FRAME.

1,076,336.

Specification of Letters Patent.

Patented Oct. 21, 1913.

Application filed March 16, 1912. Serial No. 684,192.

To all whom it may concern:

Be it known that I, SAMUEL M. VAUCLAIN, a citizen of the United States, residing in Philadelphia, Pennsylvania, have invented 5 certain improvements in Locomotive-Frames, of which the following is a specification.

My invention relates to certain improvements in the forward frame of a locomotive. 10 The object of the invention is to make a one-piece structure to which are attached the side frames, the cylinder castings and the bumper, so that the side frames of the locomotive can be discontinued at the rear of the 15 cylinder castings; the cylinder castings being firmly secured to the forward frame.

In the accompanying drawings: Figure 1, is a side view of sufficient of the forward frame of a locomotive to illustrate my invention, the wheels being shown by dotted lines; the other parts, which do not relate 20 to the invention, are omitted to avoid confusion. Fig. 2, is a plan view; and Fig. 3, is a transverse section on the line 3—3, Fig. 1.

25 Referring to the drawings, A is the forward frame of the locomotive, made as clearly shown in the drawings and having a rear extension A' to which the side frames B, B of the locomotive are secured. In the 30 present instance, the extension A' has a horizontal web a and depending flanges a'. Each flange has a vertical rib a'. The side frames B are recessed at b, b to fit these ribs and bolts b' extend through the openings in 35 the side frames and the flanges, firmly securing the two parts together. In the present instance, vertical keys c are located in the recesses b to take up any lost motion between the two parts. At the forward end 40 of the frame A is the bumper extension A' made with an opening e directly above the forward truck and ribbed for strength, as shown. The bumper is secured to the face e', forming the end of the forward frame.

45 As shown in Fig. 3, the body of the frame A has depending flanges f and is reinforced by ribs f'. The top plate f' of the body portion is solid and raised slightly at the edges, as shown, so that the cylinder castings 50 will accurately fit on the frame. D, D are the cylinder castings, each, in the present instance, having a cylinder opening D' and a valve chest D'. At the inner edge of the upper portion of each cylinder casting is a 55 vertical flange d. The flange of one cylinder

casting abuts that of the other cylinder casting; the two flanges being firmly secured together by a series of bolts g. The flanges of the cylinder castings are continued to form a horizontal flange d' on each casting and a 60 vertical flange d' at the lower portion of each casting. Each horizontal flange d' rests directly upon the upper surface of the forward frame A, while the flange d' of each casting rests against 65 the depending flange f of said frame A. Bolts h pass through openings in the flanges d' and in the top plate f' of the frame A, and bolts i pass through openings in the flanges d' and in the flanges f of the 70 said frame. Thus each cylinder casting is firmly secured to the body portion by a series of vertical bolts and by a series of horizontal bolts. This construction is especially adapted for large locomotives in which the 75 cylinder castings can be rigidly held and which obviate the necessity for extremely long side frames, as the side frames are rigidly secured to the rear end of the forward frame and the cylinder castings have a 80 greater bearing on the forward frame than they would have on the side frames, if they were extended past the said cylinder castings. Furthermore, this construction makes a very rigid support for the bumper and the 85 parts mounted on the forward end of the locomotive.

I claim:

1. The combination in a locomotive, of a forward frame having a top plate and depending flanges; rearward extensions to which the side frames of the locomotive are secured; and a forward extension forming a bumper frame; with two cylinder castings mounted one on each side of the 90 main frame, and secured to the top plate and to the side flanges of the said main portion of the forward frame.

2. The combination in the forward frame of a locomotive having a main body portion 100 consisting of a top plate and depending flanges, and ribs extending under the top plate from one flange to the other and having a forward extension, also ribbed and forming a bumper support; a rearward extension having a top plate and depending flanges shaped to receive the forward end portions of the side frames of the locomotive; means for securing said side frames to the rear extensions of 105 110

the forward frame; cylinder castings mounted on each side of the body portion of the forward frame and each having a horizontal and a vertical flange; bolts passing through openings in said horizontal and vertical flanges and through openings in the top plate and flanges of the forward frame, and abutting flanges on each cylinder casting; with means for securing the two cylinder casting flanges together and to the forward frame.

3. The combination in a locomotive, of a forward frame having a top plate and depending flanges; with two cylinder castings mounted one on each side of the frame and secured to the top plate and to the side flanges of the frame.

4. The combination in a locomotive, of a forward frame having a body portion; cylinder castings secured to said portion; a rear extension of the frame having a horizontal web and a depending flange at each

side; and side frame terminating at the rear of the cylinder castings and secured to the flanges of the rear extension.

5. The combination in a locomotive, of a forward frame having a body portion; cylinder castings secured to the body portion, said frame having a rear extension consisting of a horizontal web and side flanges; a vertical rib on each side flange; side frames terminating at the rear of the cylinder castings and recessed to receive the ribs; vertical keys in the recesses; and transverse bolts securing the side frames to the flanges of the frame.

In testimony whereof, I have signed my name to this specification, in the presence of two subscribing witnesses.

SAMUEL M. VAUCLAIN.
